FIG. 3 -

FIG. 2 -

UNITED STATES PATENT OFFICE.

HOMER CLYDE SNOOK AND GEORGE HERBERT WHITE, OF PHILADELPHIA, PENNSYLVANIA, ASSIGNORS TO ROENTGEN MANUFACTURING COMPANY, OF PHILADELPHIA, PENNSYLVANIA, A CORPORATION OF PENNSYLVANIA.

X-RAY TUBE.

1,165,138.

Specification of Letters Patent. Patented Dec. 21, 1915.

Original application filed April 7, 1911, Serial No. 619,462. Divided and this application filed November 17, 1911. Serial No. 660,787.

To all whom it may concern:

Be it known that we, HOMER CLYDE SNOOK and GEORGE HERBERT WHITE, citizens of the United States, residing at Philadelphia, in the county of Philadelphia and State of Pennsylvania, have invented new and useful Improvements in X-Ray Tubes, of which the following is a specification.

Our invention relates to X-ray tubes, and more particularly to the structure thereof.

Our invention resides in improvements in the structure and mode of mounting or supporting the anode or target; resides in the structure of the target or anode; resides in the form of the cathode; and resides in other features hereinafter described and claimed.

For an illustration of one of the forms our invention may take, reference is to be had to the accompanying drawing, in which:

20 Figure 1 is a side elevational view of our improved X-ray tube. Fig. 2 is a sectional view on the line 2—2 of Fig. 1. Fig. 3 is a cross sectional view on the line 3—3 of Fig. 1 through the target or anode.

25 The X-ray tube comprises the usual glass bulbous portion X, the integral glass tubular stems 1 and 2, and the vacuum regulator 3. At 4 is indicated the glass tip at which the exhausting or pumping is performed 30 and which is sealed off when the proper degree of vacuum within the X-ray tube is procured.

The target or anode proper is a block or sheet of platinum or other suitable refractory material 5, secured upon the plug 6

35 fitting in a hole or bore in the mass 7 of copper or other suitable material. The plug 6 is inserted to such distance that the outer surface of the plate 5 is somewhat below the 40 surface 8 of the member 7. The member 7 has a neck 9 fitting snugly into and secured to the copper or other tubular member 10 fitting within the stem 1. This neck 9 may be bored out, as indicated in dotted lines, to 45 make the parts lighter in weight, if desired.

The tubular member 10 is longitudinally slotted at 11 and has a plurality of transverse slots 12 intersecting the longitudinal slot 11. This provides a plurality of independently yielding and resilient members which frictionally engage the inside of the glass neck 1. And the tubular member 10 itself frictionally engages the inside of the neck 1. The slotting as described, insures

that the tubular member 10 shall engage the 55 interior surface of the neck 1 at a plurality of points or over a relatively extended area, so as to frictionally hold the tube 10 and attached parts in the position shown, and prevent the tube 10 and attached parts from 60 moving under the effects of shocks and other effects, to which the tube may be subjected in shipment or in usage. By this construction the pressure per unit area on the interior of the glass stem is not made so great, 65 by our method, to effect the same total friction. That is, the strain per unit area in the glass is made low by our method, so that the danger of breakage is reduced. By our construction we secure greater friction and immovability of parts, with less concentrated strain, than by former methods using similar materials. Our construction prevents 70 not only longitudinal movement of the tube 10 and attached parts, but also rotative 75 movement thereof.

Electrically connected to the tube 1, and therefore to the target 5, is the copper or other conductor 13 hard soldered to the lip 14 integral with the tube 10. Electrically 80 joining the conductor 13 to the terminal 15 is the platinum or similar wire 16 sealed through the end of the neck 1.

As above stated, the target 5 has its surface slightly below the surface 8 of the 85 member 7. The edges of the opening around the target 5 operate as a diaphragm to sharply define the rays emanating from the target 5.

The cathode 17 has the usual concave surface 18 and is preferably turned out of a solid block of metal. Into the smaller bore 19 of the cathode 17 extends the conducting rod 20 inclosed in the inner glass stem or tube 21 which extends into the larger bore 95 22 of the cathode 17. A platinum or other conductor 23 electrically connects the rod 20 and therefore the cathode 17 with the outer terminal 24, the platinum wire being sealed within glass in the manner well understood. 100 We have found that where the external surface of the cathode 17 is parallel or substantially so, even for relatively slight distances, with the inner walls of the X-ray tube X or the neck 2, there is a bombardment from 105 that surface against the glass of the tube, tending to rupture or weaken the X-ray tube. We have found that this may be pre-

vented by sloping the exterior surface of the cathode from its front edge 25 backwardly and to smaller and smaller diameters, as indicated in the drawing. From the edge 25 the contour of the cathode 17 is curved backwardly and to smaller diameters as indicated, though it is to be understood that our invention is not limited to the precise form here shown. The emanations from the 10 external surface of the cathode are at right angles or normal to that surface. And, therefore, by the construction of the cathode substantially as herein described, these emanations where they strike the interior of the 15 stem 2 are spread out, therefore not sufficiently concentrated to so highly heat the stem locally as to cause its breakage or rupture.

In the regulating neck 3 is disposed a mass 20 26 of asbestos or other material which will liberate gas to reduce the vacuum in the X-ray tube X. With this material communicates a conductor sealed through the glass and connecting to the terminal 27. This 25 vacuum regulator is shown upon the part of the bulb X back of the target. By the location of the vacuum regulator upon the bulb proper and not upon one of the tube stems, as, for example, the anode stem 1, when a 30 slotted member 10, as described, is employed for supporting the target or anode, our arrangement prevents local heating of the inner walls of the glass stem approximate any of the slots.

35 This application is a division of our application Serial No. 619,462, filed April 7, 1911, which became Patent No. 1,010,197, November 28, 1911.

What we claim is:

1. In an X-ray tube, a target member having a front face, a plug inserted in said target member at right angles to said front face thereof, and a target supported on said plug.

2. In an X-ray tube, a target member, a 45 plug inserted in said target member at right angles to the face of said target member, and a target supported on said plug, the face of said target being beneath the face of said target member.

3. In combination, a vacuum tube, a tubular neck thereon communicating with the interior thereof, a tube engaging in said neck, and an electrode supported by said tube, said tube having a longitudinal slot extending to 50 the end of said tube remote from said electrode, said tube having transverse slots between the ends of said longitudinal slot.

4. In combination, a vacuum tube, a tubular neck thereon communicating with the interior thereof, a tube engaging in said neck, an electrode supported by said tube, said tube having a longitudinal slot extending to the end thereof opposite said electrode, and a plurality of transverse slots intersecting 65 said longitudinal slot and disposed between the ends of said longitudinal slot.

In testimony whereof we have hereunto affixed our signatures this 16th day of November, 1911, in the presence of the two sub- 70 scribing witnesses.

HOMER CLYDE SNOOK.
GEORGE HERBERT WHITE.
